PONTOON BOAT

Herchel Howry, 419 N. Harmon, Watonga, Okla.

Filed June 22, 1964, Ser. No. 80,509

Term of patent 14 years

(Cl. D71—1)

FIG. 1

FIG. 2

FIG. 3

I claim:

The ornamental design for a pontoon boat, as shown.
